SINK CLAMPING DEVICE
Robert A. B. Lang, Renfrew, Ontario, Canada
Filed Dec. 10, 1959, Ser. No. 858,721
6 Claims. (Cl. 4—187)

This invention relates to clamping devices for securing or clamping sinks in cabinet or counter tops.

Various types of devices have heretofore been proposed for clamping a sink to the cabinet top in which it is to be installed. Such devices usually include clamping bolts of various kinds. The bolts or the like are, of course, only accessible from beneath the cabinet top and manipulation thereof is frequently awkward and inconvenient. Moreover, rotation of a threaded member into clamping position is relatively time-consuming, especially when the member is in an awkward location. Furthermore, use of a separate threaded member results in time-consuming application of the member to the sink structure during assembly and removal of the member therefrom preparatory to effecting of the clamping step.

It is an object of this invention to provide a sink clamping device which results in rapid and easy installation of the sink, which is simple in structure and convenient to manufacture, and which is effective and satisfactory in operation.

The invention will be described with reference to the accompanying drawing, in which:

FIGURE 1 is a perspective view of a clamping device in accordance with the invention,

FIGURE 2 is a side elevation of the device shown in FIGURE 1 in association with a sink structure,

FIGURE 3 is a perspective view of a somewhat modified form of clamping device,

FIGURE 3a is a perspective view of a further modified form of clamping device,

FIGURE 4 is a sectional side elevation of another modified form of clamping device, and

FIGURE 5 is a sectional side elevation of still another modified form of clamping device.

Referring to FIGURES 1 and 2, 1 is a metal plate which is adapted to be welded or otherwise secured to the side wall of a sink 2, 3 is a clamping arm releasably hinged to plate 1, and 4 is a supporting leg for adjustably connecting arm 3 and plate 1.

Plate 1 is preferably of unitary channel-shaped form having edge flanges 5 extending perpendicularly from the body portion of the plate. A series of angularly directed recesses or notches 6 are formed in each flange 5 adjacent one end thereof adjacent the conventional edge flange 7 of the sink. Each notch 6 of one flange is laterally aligned with a notch 6 of the other flange.

Arm 3 is also preferably of unitary channel-shaped form having edge flanges 8. Fixed to the arm adjacent one end thereof is a pin 9 having its ends projecting laterally outwardly from the flanges 8. Thus, the end portions of pin 9 are adapted to be selectively and releasably seated in one pair of laterally aligned notches 6 of plate 1. Arm 3 has a width slightly less than that of plate 1 whereby the flanges 8 will readily fit between the flanges 5 of the plate. The edges of flanges 8 are serrated as indicated at 10 to provide biting frictional engagement with the under surface of cabinet top 11.

2

Leg 4 may also be of unitary channel form with edge flanges 12. Leg 4 has a curved tongue 13 at one end thereof for releasable hinge connection with the other end of arm 3, the latter having an opening 14 for reception of the tongue 13. The other end edge 15 of leg 4 is adapted to be selectively seated in a laterally aligned pair of teeth or ratchets 16 formed in the edges of flanges 5 of plate 1. It will be apparent that the width of leg 4 is slightly greater than that of plate 1 whereby the flanges 12 will be located outside the flanges 5 of plate 1 and the flanges 8 of arm 3. An alternative arrangement is shown in FIGURE 3a wherein the flanges 12c of leg 4a are reversely directed and provided with outwardly extending marginal portions 12a. It will be apparent that the end edges 12b of portions 12a constitute the ratchet engaging surfaces of the leg.

In operation, arm 3 with leg 4 or 4a hinged thereto is selectively positioned in one pair of notches 6, such pair of notches being located above the bottom surface 20 of the cabinet top 11. It will be apparent that selection of an appropriate pair of notches will depend upon the thickness of the cabinet top. The provision of a choice of pairs of notches at varying levels makes possible use of the device with a conventional range of cabinet top thicknesses. Preferably, the pin 9 has a friction fit with the walls of the notches whereby the arm maintains its hinged connection with plate 1 during subsequent handling of the sink.

The sink is then placed through the hole 18 in the cabinet top with its flange 7 seated on the top 11, as clearly shown in FIGURE 2. It will be apparent that the arm 3 and leg 4 or 4a hinged thereto will hang freely downwardly from the pin 9 seated in notches 6. Arm 3 is now swung outwardly about its hinge connection with plate 1 and is pushed upwardly until the serrated edges 10 engage the lower corner area of top 11, and the hinged leg 4 or 4a is swung inwardly and upwardly under pressure to cause the serrated edges 10 to bite into the corner of top 11, as shown in FIGURE 2, the edge of leg 4 or 4a being in engagement with ratchets 16 and being held thereby in clamping position when pressure is released and the top 11 firmly clamped between arm 3 and sink flange 7.

Preferably leg 4 is provided with a hole, recess or indentation 19 intermediate its ends for reception of the end of a tool such as a screwdriver for application therethrough of manual pressure on the leg to force it upwardly into clamping position. In FIGURE 3a, instead of an indentation 19 there is provided a hole 19a.

It will be apparent that the placing of the arm 3 and leg 4 into position and the application of a sharp blow to leg 4 are all that is required to complete the clamping operation. This procedure requires only a few seconds and thus an extremely rapid and easy installation procedure results from use of the device described.

FIGURE 3 illustrates a slightly modified form of the invention wherein the upper end of a plate 1a is provided with a portion 20 which lies in a plane spaced outwardly from the plane of the remaining portion thereof. Portion 20 has a series of recesses or slots 21 therein to selectively receive a curved tongue 22 on the end of arm 3a. It will be apparent that this structure provides an alternative form of hinge connection between arm 3a and plate 1a.

Referring to FIGURE 4, the modified form therein illustrated comprises a plate 23 adapted to be welded or otherwise secured to the side wall of sink 2. Plate 23 has a main body portion 24 which lies in a plane spaced outwardly from the wall of sink 2 to provide an intervening space 25. A toggle 26 comprises an arm 27 having a supporting leg 28 pivotally attached thereto at 29 to provide a toggle joint connection therebetween. Arm 27 has an extension 27a below the pivot point 29, extension 27a having a surface 27b engageable by the leg 28 to limit outward swinging movement of the leg 28 and to define the closed or clamping position of the toggle. Leg 28 has a projecting tongue 30 arranged for selective reception in one of a series of holes 31 in body portion 24 to provide a releasable hinge connection between leg 28 and plate 23. Arm 27 has a free end portion 32 arranged for biting engagement with the lower surface of cabinet top 11.

With the sink 2 in position, the end 32 of arm 27 is applied to an appropriate location on the under surface of top 11 (say, one inch from the edge of the sink hole). With the arm 27 and leg 28 in angular relation to each other, i.e., with the toggle in released position, the tongue 30 is placed in a selected hole 31 (depending upon the thickness of top 11). Thereafter, the toggle is snapped into closed position as shown in the drawing to cause the sink flange 7 to be firmly clamped onto the cabinet top 11.

Referring to FIGURE 5, a somewhat similar type of toggle clamping device is therein illustrated. A plate 33 is fixed to the wall of sink 2 and has a shoulder or pocket 34 thereon. The toggle 35 comprises an arm 36 one end of which is provided with a projection 37 for biting engagement with cabinet top 11 and the other end portion 38 of which is in slightly angular relation to the remaining portion. Portion 38 has an end tab 39 for application of manual pressure thereto. A leg 40 is pivoted at 41 to arm 36 at the juncture of end portion 38 with the remaining portion thereof.

In operation, with the sink in position, the arm 36 is placed with its projection 37 in proper relation to the cabinet top. With the toggle released, the end of leg 40 is placed in pocket 34 and the toggle closed by applying pressure on arm 36 at tab 39 to align the arm 36 and leg 40 and to clamp the sink firmly in place. It will be observed that the clamping position is defined by positioning of the end portion 38 of arm 36 in approximate engagement with shoulder 34.

I claim:

1. In a sink having a side wall, said side wall having an external surface, and an edge flange extending outwardly from said side wall surface in substantially perpendicular relation thereto, an installation clamp therefor comprising a member fixed to said side wall external surface and underlying said flange, said member having an upper portion adjacent said sink edge flange and a lower portion remote from said sink edge flange, said member lower portion having a plurality of vertically spaced teeth, a clamping arm having one end swingably mounted to said member upper portion and having a support-engageable surface, said arm being swingable outwardly from said member into angular relation thereto to place said support-engageable surface in opposed relation to said sink edge flange, and means fixing said arm in said angular relation comprising a leg having one end pivoted to the other end of said arm and its other end freely seated on one of said teeth.

2. In a sink having a side wall, said side wall having an external surface, and an edge flange extending outwardly from said side wall surface in substantially perpendicular relation thereto, an installation clamp therefor comprising a plate fixed to said side wall external surface and underlying said flange, said plate having an upper portion adjacent said sink edge flange and a lower portion remote from said sink edge flange, said plate lower portion having a pair of substantially parallel flanges each

disposed in substantially perpendicular relation to said sink edge flange, each said plate flange having a plurality of vertically spaced teeth in its free edge, a clamping arm having one end pivotally mounted in said plate upper portion and having a support-engageable surface, said arm being swingable outwardly from said plate into angular relation thereto to place said support-engageable surface in opposed relation to said sink edge flange, and means fixing said arm in said angular relation comprising a leg having one end pivoted to the other end of said arm and its other end freely seated on a respective pair of said teeth.

3. In a sink having a side wall, said side wall having an external surface, and an edge flange extending outwardly from said side wall surface in substantially perpendicular relation thereto, an installation clamp therefor comprising a member fixed to said side wall external surface and underlying said flange, said member having an upper portion adjacent said sink edge flange and a lower portion remote from said sink edge flange, said member lower portion having a plurality of vertically spaced teeth, said member upper portion having a series of recesses therein, said recesses being aligned in a direction perpendicular to said sink edge flange and in varying spaced relation thereto, a clamping arm having one end swingably seated in a selected one of said recesses and having a support-engageable surface, said arm being swingable outwardly from said member into angular relation thereto to place said support-engageable surface in opposed relation to said sink edge flange, and means fixing said arm in said angular relation comprising a leg having one end pivoted to the other end of said arm and its other end freely seated on one of said teeth.

4. In a sink having a side wall, said side wall having an external surface, and an edge flange extending outwardly from said side wall surface in substantially perpendicular relation thereto, an installation clamp therefor comprising a plate fixed to said side wall external surface and underlying said flange, said plate having an upper portion adjacent said sink edge flange and a lower portion remote from said sink edge flange, said plate lower portion having a pair of substantially parallel flanges each disposed in substantially perpendicular relation to said sink edge flange, each said plate flange having a plurality of vertically spaced teeth in its free edge, said plate upper portion having a series of recesses therein, said recesses being aligned in a direction perpendicular to said sink edge flange and in varying spaced relation thereto, a clamping arm having one end swingably seated in a selected one of said recesses and having a support-engageable surface, said arm being swingable outwardly from said plate into angular relation thereto to place said support-engageable surface in opposed relation to said sink edge flange, and means fixing said arm in said angular relation comprising a leg having one end pivoted to the other end of said arm and its other end freely seated on a respective pair of said teeth.

5. In a sink having a side wall, said side wall having an external surface and a horizontal edge flange extending outwardly from said side wall surface in substantially perpendicular relation thereto, an installation clamp therefor comprising a member fixed to said side wall external surface and underlying said flange, said member having a series of vertically spaced holes therein, an arm having a support-engageable end adjacent said edge flange, and a leg having a pivotal connection with said arm at a point below said support-engageable end, said arm having an extension below said pivotal connection and a surface on said extension engageable by said leg to limit swinging movement of said leg relatively to said arm outwardly of said side wall surface, said leg having a portion freely seated in one of said holes, said leg being swingable into engagement with said extension surface to define a clamping position.

6. In a sink having a side wall, said side wall having

an external surface and a horizontal edge flange extending outwardly from said side wall surface in substantially perpendicular relation thereto, an installation clamp therefor comprising a member fixed to said side wall external surface and underlying said flange, said member having a shoulder thereon underlying said flange and in spaced relation thereto, an arm having a support-engageable end and an angularly extending end portion remote from and below said support-engageable end and disposed laterally outwardly of said shoulder, and a leg 10 pivoted to said arm at a point adjacent said angularly extending end portion and having a free end below said

pivot point seated on said shoulder, said leg being swingable into aligned relation with said arm to define a clamping position in response to movement of said angularly extending end portion of said arm towards said shoulder.
